UNITED STATES PATENT OFFICE

169,380

BEVERAGE CARRIER

Paul D. McGee, Chicago, Ill., assignor to Superior
Plastics Inc., Chicago, Ill., a corporation of Delaware

Application January 21, 1953, Serial No. 23,227

Term of patent 14 years

(Cl. D44—7)

To all whom it may concern:

Be it known that I, Paul D. McGee, a citizen of the United States, residing at Chicago, in the county of Cook and State of Illinois, have invented a new, original, and ornamental Design for a Beverage Carrier, of which the following is a specification, reference being had to the accompanying drawing, forming part thereof.

Fig. 1 is a plan view of a beverage carrier, showing my new design;

Fig. 2 is a side elevational view thereof;

Fig. 3 is a sectional view thereof on the line 3—3 of Fig. 2; and

Fig. 4 is a sectional view thereof on the line 4—4 of Fig. 2.

I claim:

The ornamental design for a beverage carrier, substantially as shown.

PAUL D. McGEE.
